DESIGN FOR A LIGHT EMITTING DECORATIVE DEVICE

Elmer J. Graf, Roselle Park, N. J.

Application January 21, 1935, Serial No. 54,975

Term of patent 7 years

To all whom it may concern:

Be it known that I, Elmer J. Graf, a citizen of the United States, residing at Roselle Park, in the county of Union, State of New Jersey, have invented a new, original, and ornamental Design for a Light-Emitting Decorative Device, of which the following is a description, reference being had to the accompanying drawing, forming a part thereof.

In the drawing,

Figure 1 is a front elevational view of the light-

emitting decorative device, including the holder and light-emitting members, this view being substantially twice the size of the commercial article.

Figure 2 is a side elevation of the device shown in Figure 1.

I claim:

The ornamental design for a light-emitting decorative device, as shown.

In testimony whereof, I affix my signature.

ELMER J. GRAF
